UNITED STATES PATENT OFFICE.

SIDNEY D. INSCHO, OF SHELBY, OHIO.

MEMORANDUM OR PAD HOLDER.

1,110,488.

Specification of Letters Patent. Patented Sept. 15, 1914.

Application filed September 19, 1913. Serial No. 790,669.

To all whom it may concern:

Be it known that I, SIDNEY D. INSCHO, a citizen of the United States of America, residing at Shelby, in the county of Richland 5 and State of Ohio, have invented certain new and useful Improvements in Memorandum or Pad Holders, of which the following is a specification.

My invention relates to memoranda or 10 pad holders.

The objects of my invention are to provide a simple and efficient structure by 15 means of which a pad of leaves or the like can be easily and conveniently secured to and removed from the back or support, and further to provide means for securely holding or locking the pad to the back or support, by engagement with a flap that is secured to the pad, or, in lieu thereof, through 20 the medium of a plurality of the leaves of the pad.

Other objects of my invention are to provide means whereby lifting of the pad from 25 locked position, releases the locking means and permits the pad to be removed from the back, and in replacing the pad to allow the pad to be dropped by gravity, onto the back and then by the act of pressing downward 30 on the top of the pad, adjacent to the top end, moving the holding or locking means to lock the pad in place on the back, in position ready for use.

I attain these and other objects by the means illustrated in the accompanying 35 drawing, in which:

Figure 1 is a perspective view of the bail or locking means showing same detached from the back; Fig. 2 is a side view of the invention showing the pad in locked position; Fig. 3 is a side view, showing the bail 40 in position to permit the pad to be removed; Fig. 4 is an end view of the invention showing the pad removed; and Fig. 5 is a fragmentary top plan view.

In the drawings, reference numeral 1 represents a back to which is suitably attached 45 a plate 2 provided with a bearing 3.

The pad locking means or bail is preferably made of an integral piece of wire 50 which latter is formed and arranged in such manner as to perform the functions hereinbefore described.

The bail, generally designated A in the 55 drawings is provided with a flap or leaf engaging member 11, which latter extends transversely of the back 1, the end portions

9 and 10 of the member 11 being bent at right angles thereto and being further bent to form short parts 7 and 8, respectively which latter extend toward each other and are disposed parallel with the member 11. The parts 7 and 8 are further extended inwardly toward the member 11 to provide arms 5 and 6, respectively, the arms 5 and 6 being extended inwardly toward each other 65 at 4, 4, to conjointly provide a journal which latter is disposed in parallelism with the member 11.

The journal 4 of the bail is received in the bearing 3 and when in the position shown 70 in Fig. 3 the flap 12, or a plurality of leaves 13 of the pad, is inserted beneath the member 11, whereupon said member 11 is swung down toward the back 1 to clamp the flap 12 against the back 1, in which position the 75 parts 9 and 10 assume an inclined position (see Fig. 2) with reference to the plane of the back forcing the end C of the pad in frictional contact with the parts 7 and 8 thereby binding and locking the pad to the 80 bail and back, between the member 11 and the parts 7 and 8.

The peculiar formation of the bail provides means for securely locking the pad to the back and also means capable of easy 85 manipulation for purpose of releasing the pad.

When desired to remove the pad and replace it with another, for any reason, the pad is swung upward which movement 90 swings the pad holder upon its pivotal connection, causing the parts 7 and 8 to move out of engagement with the pad end C, thereby automatically releasing the pad from its locked position, whereupon the pad 95 can then be readily removed from the bail.

The parts 9 and 10 prevent the pad from slipping laterally.

What is claimed is:

1. A device of the class described, comprising a back, a plate provided with an elongated bearing attached to said back along the upper edge thereof, a bail provided with an elongated journal located in said elongated bearing having upwardly 100 and outwardly extending portions to engage the vertical ends of the pad and side portions bent at an angle to the outwardly extending portions; said bail having a part upon which the pad is mounted and which 105 connects said side portions to engage the pad sides.

2. A device of the class described comprising a back, a plate provided with an elongated bearing attached to said back along the upper edge thereof, a bail made of wire formed to provide an elongated journal portion; thence bent from the journal portion, upwardly, outwardly and laterally and a part connecting the lateral portions to provide means for mounting the pad 10 upon said bail.

3. A device of the class described comprising a back, a plate provided with an elongated transverse bearing attached to said back, a bail made of wire comprising a 15 journal portion and portions contiguous therewith bent upwardly; thence outwardly; thence at right angles with the journal, a part connecting the right angle bends arranged parallel with the journal; said right 20 angles of said bail being disposed to provide for automatically locking the pad to the back and to release it therefrom by swinging the pad to or from said back.

4. A pad holder consisting of a base, and

locking means thereon having a lower portion directly pivoted to the base and a second free portion which is movable toward and away from the base, and connecting means for said parts to engage the vertical end and the sides of the pad whereby when the locking means is engaged with the pad and moved to seat the latter on the base, the pad will be automatically locked to the base.

5. A pad holder consisting of a base, and 25 locking means pivoted thereon and formed to engage the vertical end and the sides of the pad to prevent endwise and lateral movement respectively of the pad except when the pad is raised up from the base to 30 move the locking means out of engagement with the pad end and sides.

In testimony whereof I affix my signature in presence of two witnesses.

SIDNEY D. INSCHO.
